UNITED STATES PATENT OFFICE

URBAN R. BECK AND HUGO A. STOLLENBERG, MILWAUKEE, WISCONSIN

MOTOR VEHICLE WINDOW

Application filed March 22, 1930. Serial No. 438,046.

This invention relates generally to doors and more particularly to new and useful improvements in vehicle doors, such as are used on automobiles, and has for its primary object to provide, in a manner as hereinafter set forth, a door of this character having a vertically slideable window therein and further including what may be termed a supplemental window mounted operatively on the usual main window and adapted for actuation independently thereof for providing means for ventilating the vehicle properly or for providing a comparatively small opening for any desired purpose without the necessity of opening the usual window.

Another very important object of the invention is to provide a door of the character described embodying novel means common to the windows whereby same may be actuated independently of each other when desired, that is, the supplemental or ventilating window may be moved to its open or closed position when the main window is in raised or closed position.

Other objects of the invention are to provide a door for vehicles of the aforementioned character which will be simple in construction, strong, durable, efficient and reliable in operation and which may be manufactured at low cost.

All of the foregoing and still further objects and advantages of the invention will become apparent from a study of the following specification, taken in connection with the accompanying drawing wherein like characters of reference designate corresponding parts thruout the several views and wherein:

Figure 1 is a view in side elevation looking at a door in accordance with this invention from the outer side thereof, said door having a portion thereof broken away to reveal the window operating mechanism.

Fig. 2 is a view in horizontal section through the windowed portion of the door.

Fig. 3 is a vertical cross sectional view taken substantially on the line 3-3 of Fig. 1, looking in the direction indicated by the arrows.

Fig. 4 is a detail view in perspective view

of the bell crank lever which constitutes one of the elements for actuating the ventilating window.

Referring now to the drawing in detail, it will be seen that the door is designated generally by the reference numeral 1 and is formed with a substantially rectangular window opening in its upper portion. The door 1 includes the spaced inner and outer walls 2 and 3 respectively which provide a well 4 with which the window opening communicates through a slot or opening 5.

Guide channel members 6 are provided on the vertical walls of the window openings and across the top wall of said window openings, and vertically slideable in the guide channel members is a substantially rectangular frame 7 which forms a part of the window 8 which terminates, at one end, in spaced relation to the corresponding end of the window opening.

As will be obvious, the window is operable through the opening or slot 5 for disposition in the well 4 when said window is to be lowered.

A ventilating window is mounted for swinging movement in a horizontal plane in the frame 7 adjacent the free vertical edge of the window 8 and comprises a suitable frame 9 having the glass 10 therein. The side of the frame 9 which is adjacent the free vertical edge of the window 8 is provided, on its upper and lower ends, with trunnions which are journaled in suitable bearings provided therefor in the upper and lower sides of the frame 7, the lower trunnions extending downwardly through the frame 7 and having fixed on its lower end portion an arm 11.

As best seen in Fig. 2 of the drawing, the ventilating window, when closed, is disposed in the plane of the main window 8 and when so disposed, is adapted to be moved up and down with said main window 8 when the main window 8 is in raised position the ventilating window is adapted to be swung outwardly as indicated in broken lines in Fig. 2 of the drawing, through the medium of a mechanism which will now be described.

A flat, metallic plate 12 is rigidly secured to the lower side of the frame 7 and depends

therefrom in the well 4 of the door. The plate 12 is provided with a slot which includes a horizontal portion 13 which merges with an upwardly directed, arcuate portion 14. A bell crank lever 15 is mounted for swinging movement in a vertical plane on one side of the plate 12, one arm of the bell crank lever being comparatively wide and being operatively connected to the arm 11 of the ventilating window through the medium of a rod 16, said rod 16 having one end pivotally connected to the free end portion of the comparatively large arm of the bell crank lever 15 and its other end pivotally connected to the free end portion of the arm 11. The other arm of the bell crank lever 15 extends adjacent the arcuate portion 14 of the slot in the plate 12. The comparatively wide arm of the bell crank lever 15 is recessed on one side and adjacent the other arm of said bell crank lever, as at 17.

A spring 18 has one end connected to the plate 12 and its other end connected to the free end portion of the depending arm of the bell crank lever 15 in a manner to yieldingly urge and maintain the ventilating window in its closed position.

A segmental gear 19 is rotatably mounted, as at 20, in the well 4 of the door 1 and is in mesh with a pinion gear 21 which is fixed on the inner end portion of a shaft 22 which is journaled in the inner wall 2 of the door and which has fixed on its other end portion an operating crank 23. Extending from the segmental gear 19 is an arm 24 which extends adjacent one side of the plate 12 and has mounted rigidly on its free end portion the laterally extending fin 25.

The pin 25 projects through the slot in the plate 12 and is operatively engageable with the bell crank lever 15, as will be obvious.

In operation, when the arm 24 is swung downwardly from the position shown in Fig. 1 of the drawing, the pin 25 travels in the horizontal portion 13 of the slot in the plate 12 for lowering the main and ventilating windows, it being understood, of course, that the ventilating window is in its closed position. When the arm 24 is again swung upwardly the pin 25 travels in the opposite direction in the horizontal portion 13 of the slot and the windows are, of course, raised.

When the windows have reached the limit of their upward movement, the arm 24 is in the position seen in Fig. 1, and is about to enter the arcuate portion 14 of the slot. Upon continued upward movement of the arm 24 to the position indicated in broken lines in Fig. 1 of the drawing, the pin 25 travels in the arcuate portion 14 of the slot. When the pin moves upwardly through the arcuate portion 14 of the slot, it engages the depending arm of the bell crank lever 15 and actuates said bell crank lever in a manner to swing the ventilating window outwardly

through the medium of the rod 16 and the arm 11.

The recess 17 in the bell crank lever 15 receives the pin 25 when said pin is substantially in its uppermost position and in addition provides a shoulder with which the pin is engageable upon downward swinging movement of the arm 24, for positively actuating the bell crank lever for swinging the ventilating window to its closed position.

This means for moving the ventilating window toward its closing position is in addition to the spring 18. The spring 18 must not be strong enough to close the ventilating window by itself.

It is believed that the many advantages of a structure in accordance with this invention will be readily understood, and although the preferred embodiment of the invention is as illustrated and described, it is to be understood that changes in the details of construction and in the arrangement of parts may be resorted to which will fall within the scope of the invention as claimed.

Having thus described our invention, what we claim as new is:

1. A structure of the character described comprising a frame, means for slidably supporting the frame, a window fixed in the frame, another window mounted for swinging movement in the frame, a plate secured to the frame and having a slot therein including straight and arcuate portions, an arm mounted for swinging movement on a supporting structure, means for actuating the arm, a pin on the arm operable in the slot in a manner to actuate the frame, upon movement of said pin in the straight portion of the slot, and means operable by the arm for swinging the second-named window when the first-named window is in its closed position.

2. A structure of the character described comprising a frame, means for slidably supporting the frame, a window fixed in the frame, another window mounted for swinging movement in the frame, a plate secured to the frame and having a slot therein including straight and arcuate portions, an arm mounted for swinging movement on a supporting structure, means for actuating the arm, a pin on the arm operable in the slot in a manner to actuate the frame upon movement of said pin in the straight portion of the slot, means operable by the arm for swinging the second-named window when the first-named window is in its closed position, the last-named means comprising a bell crank lever mounted for swinging movement on the supporting structure and disposed for engagement and actuation by the pin when said pin moves in the arcuate portion of the slot, and a rod operatively connecting the bell crank lever to the second-named window.

3. A window structure of the class de-

scribed comprising a frame having a window opening therein, a vertically movable sash supported in the frame, a second sash co-operating with the first sash to close the window opening, said second sash being vertically movable with the first sash and pivotally connected with the first sash to pivot about a vertical axis at an edge of the first sash and common means operatively connected to the sashes for raising and lowering them and for swinging the second sash on its pivot after the two sashes have been moved to one limit of their movement.

4. A window structure of the class described comprising a frame having a window opening therein, a vertically movable frame supported by the first frame, a transparent member in the vertically movable frame terminating a distance from one end thereof, a second transparent member pivotally supported in the frame and closing the space left by the first transparent member and the pivot of said second transparent member being located in a vertical plane, and common means operatively connected to the frame and pivot for moving the frame vertically and for moving the second transparent member to open position after the frame has been moved to a position for closing the window opening and moving the second transparent member to closed position just before the frame starts to move to its open position.

5. A window structure of the character described comprising a sash designed for vertical movement in a frame, a panel mounted in said sash for oscillation upon a vertical axis, a lever oscillatably mounted in the sash and having connection with said panel for swinging the same laterally, means for effecting the vertical movement of the sash in a supporting frame, and mechanism connected with said lever adapted to be engaged by said means for actuation thereby to move said panel on its axis.

45 6. A window structure of the character described comprising a sash designed for vertical movement in a supporting frame, a panel mounted in said sash for oscillation on a vertical axis, lever means oscillatably mounted in the sash and having connection with said panel for swinging the same on its pivot, an element connected with the sash for effecting the vertical movement thereof and designed to move transversely of the sash, and means designed to be engaged by said element in its transverse movement for effecting the oscillation of said panel moving lever.
